UNITED STATES PATENT OFFICE.

WILLIAM H. POWERS AND JOSEPH H. WALKER, OF GRAND RAPIDS, MICH.

BURIAL-CASKET.

SPECIFICATION forming part of Letters Patent No. 275,265, dated April 3, 1883.

Application filed September 9, 1882. (No model.)

To all whom it may concern:

Be it known that we, WILLIAM H. POWERS and JOSEPH H. WALKER, of Grand Rapids, in the county of Kent and State of Michigan, 5 have invented certain new and useful Improvements in Burial-Caskets; and we do hereby declare that the following specification, taken in connection with the drawings furnished and forming a part of the same, is a clear, true, 10 and complete description of our invention.

Our said improvements pertain to that class of caskets which, for purposes of economic transportation and storage, are constructed in detachable sections; and the objects of our invention are to provide a burial casket or case 15 having its sides, ends, and bottom constructed in two substantially equal sections, which can be separated, transported, and put together without undue liability of defacing the highly- 20 finished surfaces and edges; and, also, to provide for the putting of the sections firmly together with a minimum of labor, and without liability of defacing surfaces or edges; and, also, 25 to so locate the vertical joints between the sections as to render the casket or case, when put together for use, in all respects equal to those built up, as heretofore, without the sectional feature.

After describing a casket embodying our invention, the features deemed novel will be specified in the several claims hereunto annexed.

Referring to the drawings, Figure 1 is a perspective view of so much of a casket as is deemed necessary for illustrating our invention. Fig. 2 is a top view of the same with its sections slightly separated. Fig. 3 is a top view of a stack of three of such caskets as arranged for transportation and storage. Figs. 4 and 5 are corner views of the interior of the 40 casket, illustrating the bracing and locking devices by which the two sections are connected, one locking-brace being provided at each end of the casket.

Each of the sides A of the casket and one 45 of the ends B are jointed permanently together by a rounded corner-piece, C, the vertical edges of which are angularly recessed to afford contact with said end and side, both endwise and sideways, substantially as heretofore in non-sectional caskets. The side and end thus joined are permanently mounted upon a

bottom board, D, or its equivalent, as a strengthening medium. A rectangular frame may be employed, in which case a separate bottom must be provided; but we prefer the 55 bottom D, as shown, without the frame-work suggested, and constructed in two sections, a and b, divided by an angular joint, and provided with a groove and a spline, c, as shown, and with heavy dowels, as at d, which occupy 60 coincident dowel-holes e in the sides of the casket. Each section of the casket is therefore a counterpart of the other, except that section a of the bottom has at the angular joint the spline c, while section b has the groove to 65 receive it; or this joint may be made by doweling together. When the sections are put together it will be seen that the section-joints are practically concealed, because the end of each side A, at its junction with a corner-piece, C, 70 presents the same offset as that presented at the permanent joints at g. The angular joint in the bottom of the casket enables on each side a sufficient length of permanent joint between each section of the bottom and the side 75 A, to which it is permanently attached, to afford the desired strength in the structure; and it also provides for a longitudinal distribution of weight on both sides of said angular joint when the casket is used, which could not be 80 the case if a rectangular joint were employed. Said angular joint also enables the two sections to be readily put together and taken apart, if need be, without cramping or interfering with the dowels, and the spline being of 85 proper width renders the bottom of the casket practically as strong as if in one piece. At each section-joint f, on the inner surface of the casket, we prefer to apply a metallic brace, h, which also serves as a lock for firmly uniting 90 the sections. Said braces are, as heretofore, angular in form, so as to properly face against the adjacent side and corner-piece, and also so that when turned backward for packing they will be practically out of the way. Each 95 brace is pivoted at one end, and is provided with a recess, h', which engages with a headed stud or screw, h², in the side of the casket. When the sections are united and the brace-locks turned down upon their studs, they draw 100 the parts firmly together and render the section-joint practically unobservable.

If desired, glue may, of course, be employed at all of the section-joints by the undertaker when preparing the casket for use, and each brace-lock, of whatever form it may be, should 5 be permanently secured in place by a screw or nail driven close against its upper edge.

It will be seen in Fig. 3 that when the caskets are packed for storage or transportation none of the finished surfaces or edges of any one 10 section are exposed to abrasion by contact with another, and that the desired economy in space is obtained.

Having thus described our invention, we 15 claim as new and desire to secure by Letters Patent—

1. A burial-casket having corner-pieces, and

constructed in separable sections, each of which includes one side, one end, two corner-pieces, and a portion of the bottom of the casket, substantially as described, whereby the section-joints are located at the junction of each side with one of said corner-pieces. 20

2. In a sectional burial-casket, the sectional bottom angularly divided, and splined and grooved or doweled at its joint, in combination with the sides of the casket, and doweled thereto, substantially as described. 25
